US00D635149S

(12) **United States Design Patent**
Viggers et al.

(10) **Patent No.:** US D635,149 S
(45) **Date of Patent:** ** Mar. 29, 2011

(54) **DISPLAY SCREEN WITH USER INTERFACE**

(75) Inventors: **Kevin Viggers**, Calgary (CA); **Giselle Goncalves**, Mississauga (CA); **Julie LaFleur**, Calgary (CA); **Ron Desnoyers**, Calgary (CA); **Jenna Pipchuk**, Calgary (CA)

(73) Assignee: **SMART Technologies ULC**, Calgary, Alberta (CA)

(**) Term: **14 Years**

(21) Appl. No.: **29/342,231**

(22) Filed: **Aug. 20, 2009**

(51) **LOC (9) Cl.** 32-00

(52) **U.S. Cl.** **D14/486**

(58) **Field of Classification Search** D14/485-495; 715/700-867

See application file for complete search history.

(57) **CLAIM**

The ornamental design for a display screen with user interface, as shown and described.

DESCRIPTION

The FIGURE is a front view for a display screen with user interface showing our new design.

The broken line display screen and portions of the user interface are included in the drawing for the purpose of illustrating unclaimed environment and form no part of the claimed design.

1 Claim, 1 Drawing Sheet
